UNITED STATES PATENT OFFICE.

LAYTON M. PARKHURST, OF ANDERSON, INDIANA, ASSIGNOR TO INDIANA DIE CASTING DEVELOPMENT COMPANY, A CORPORATION OF INDIANA.

DIE-CASTING MACHINE.

1,056,442.

Specification of Letters Patent. Patented Mar. 18, 1913.

Original application filed February 15, 1911, Serial No. 610,931. Divided and this application filed June 19, 1911. Serial No. 634,178.

To all whom it may concern:

Be it known that I, LAYTON M. PARKHURST, of Anderson, county of Madison, and State of Indiana, have invented a certain useful Die-Casting Machine; and I do hereby declare that the following is a full, clear, and exact description thereof, reference being had to the accompanying drawings.

10 This application is divided out of a former application by me, Serial No. 610,931, filed Feb. 15, 1911.

15 The object of this invention is to provide means for exhausting air from a die used in connection with a die-casting machine, particularly when the die-casting is caused by compressed air.

20 The nature of the invention will be understood from the accompanying drawings and the following description and claims.

25 In the drawings, Figure 1 is an end elevation of the upper part of a die-casting machine, the lower part being broken away. Fig. 2 is a section on the line 2—2 of Fig. 1 through a part of the device. Fig. 3 is a plan view of the machine with part of the upper portion cut away on the line 3—3 of Fig. 1. Fig. 4 is a section on the line 4—4 of Fig. 3.

30 There is shown in the drawings a frame 10 formed of two substantially similar sides, one of which appears in Fig. 1, and the two sides appear in Fig. 3. Within said frame there is a tilting or oscillatable casing 11, the same being tilted by the handle 12. A suitable melting pot 25 is provided in the casing 11. Fuel is supplied to the casing 11 through the pipes 19 and 20. The melting pot is not shown herein, but it has an outlet 40 53, see Fig. 4, and upon that outlet a die is secured so as to oscillate with the melting pot, and when in a downward position the molten metal passes from the melting pot through the outlet 53 to the die. Then the 45 melting pot and die are oscillated to the upright position shown in Figs. 1, 3 and 4 and the article removed from the die.

50 The die is formed of two members 60 and 61, the former having a recess which fits over the end of the outlet nozzle 53 from the melting pot, and it has a small inlet port 62. An air chamber 63 is formed between the members of the die surrounding and at intervals in communication with the interior

of the die so that the atmosphere in the die 55 may pass out of the die chamber into the surrounding air chamber 63 and out therefrom, and thus in no manner retard the ready and complete admission of the molten metal.

60 The die is held in place by a screw bolt 65 which extends loosely through the top of the frame 66, said frame consisting of two vertical side portions and a cross or connection portion at the top. Said side portions, as seen in Fig. 5, extend up from the casing 11. The screw bolt 65 is actuated by the wrench 67 and screws through a double-ended bar 68, the ends of which bar are oppositely beveled so as to make sharp edges 70 adapted to catch in notches 70 on the frame 66, as shown in Fig. 1. The construction is the same at each side of the frame 66. This construction is to enable the die member to be clamped with a slight movement of the lever 67. When the bar 68 is disengaged from the notches 70, the screw 65 can be lifted up entirely away from the die members. When the die members are replaced, the screw 65 can drop down into place, the bar 68 turned under notches 70 and then a very slight movement of the lever 67 will complete the clamping. The screw bolt 65 is held in its upward position by a pivoted 75 latch 72 on the frame 66 adapted when moved to slip in between the threads of the bolt 65 and hold it up out of the way of the die while the die is being arranged in place.

80 The upper member 61 of the die has conduits 163 leading from the chamber 63 to an outlet 164 from said die. A head 165 is placed in connection with the member 61 and held in place by the screw 65, said screw clamping the parts 165, 61, 60 and 53 together. The head 165 has a suction chamber 90 166 in communication with the outlet 164 from the die. There is also a tubular extension 167 connected with the head 165 and in communication with the chamber 166 therein. To said tubular extension a tubular arm 168 is pivoted, as seen in Fig. 4, and to the tube 168 another tube 169 is pivoted, and said latter tube is pivotally connected with a vertical tube 175, which is secured to the extension 176 screwing on the hub 126 of the 100 melting pot 25 and in communication with the passageway 177 longitudinally through the hub, which, when the pot is inverted, is 105

in communication with the tubular projection 178 in the cap 179, which is loosely mounted on the hub 126 of the melting pot, and down from the projection 178 a suction pipe 180 extends to a suction pump, not shown. With this mechanism when the pot is inverted and the metal enters the die, the tubes 177 and 178 will be in communication and the air will be exhausted from the die 10 chamber so that the chamber will be entirely filled by the molten metal.

I claim as my invention:

15. 1. A die casting machine including an oscillatory melting pot, a die construction, a flexible conduit between the melting pot and die construction for exhausting air from the latter, and means controlled by the oscillatory movement of the melting pot for controlling the exhaust of air from the die.
20. 2. A die casting machine including an oscillatory melting pot with a suitable outlet nozzle having a hub extending from the side of the melting pot and having an air passage through it away from its center, a bearing 25. for said hub provided with an exhaust air passageway adapted to register with the passage in said hub when the melting pot is

tilted, a suitable die construction, and a flexible conduit between said die construction and the passageway in the hub of the 30 melting pot for exhausting the air from the die.

3. A die-casting machine including dies having a plurality of gates with their adjacent surfaces formed so as to provide an 35 escaping air chamber in communication with the main die chamber and one of said gates having passageways from said escaping air chamber, an air exhaust head, means for clamping said air exhaust head and die 40 gates together said exhaust head being in communication with the passageway in said die gate, a fixed air exhaust pipe, and a flexible conduit extending from said air exhaust head to said stationary exhaust 45 pipe.

In witness whereof, I have hereunto affixed my signature in the presence of the witnesses herein named.

LAYTON M. PARKHURST.
